UNITED STATES PATENT OFFICE.

CHARLES JOHN KAY, OF AURORA, ILLINOIS, ASSIGNOR TO WESTERN ELECTRIC COMPANY, INCORPORATED, OF NEW YORK, N. Y., A CORPORATION OF NEW YORK.

FILING APPARATUS.

Application filed January 22, 1925. Serial No. 3,904.

This invention relates to filing apparatus, and more particularly to cabinets for filing sheets of material.

The object of this invention is to provide an improved apparatus for filing sheets of material.

In accordance with the main features of the invention a filing cabinet is provided wherein folders, comprising rigid backs and flexible covers serve to hold flat material, such as drawings, and are inserted in horizontally disposed compartments formed by a plurality of closely spaced frames which serve to maintain the drawings under pressure. Conveniently positioned slidable shelves also assist in handling the folders.

Other features and advantages of the invention will readily become apparent from the following detailed description and the accompanying drawings in which

Fig. 1 is a perspective view of a cabinet embodying the invention and showing one of the slidable rests in position to support a folder;

Fig. 2 is a horizontal section of the cabinet taken on the line 2—2 of Fig. 3 looking in the direction indicated by the arrows;

Fig. 3 is a front elevation of the cabinet;

Fig. 4 is an enlarged vertical section of a portion of the cabinet taken on the line 4—4 of Fig. 3 looking in the direction indicated by the arrows and showing one folder in position;

Fig. 5 is an enlarged detail view showing a folder being positioned between adjacent frames;

Fig. 6 is an enlarged plan view of one of the folders;

Fig. 7 is a section thereof taken on the line 7—7 looking in the direction indicated by the arrows;

Fig. 8 is a perspective view of one of the frames that form the compartments, and

Fig. 9 is a perspective view of one of the shelves and the grooved portion of the frame in which it is slidably secured.

In the drawings in which like reference numerals designate like parts throughout the several views, 10 denotes generally the improved filing cabinet which comprises a plurality of legs 11, a pair of sides 12, a back 13, and a top 14. Secured to the sides 12 are a plurality of supporting strips 16 which hold a plurality of frames 17 in evenly spaced positions. The back 13 is

provided with similar strips 18 (Fig. 4) which serve a like purpose. A plurality of folders indicated at 20 (Fig. 6) are provided which comprise a pressboard back or bottom 22 and a flexible top or cover 23, preferably of canvas, which is sewed to the bottom 22 along the edge 24 thereof. When filed, the folders lie in compartments 26 formed between adjacent frames 17, the height of each compartment being such that a filled or a partially filled folder is placed under suitable pressure to properly maintain the material therein. The edges of the frames 17 are beveled at 27, as shown in Fig. 5, to assist in admitting the folders 20, and are provided with recesses 29 to facilitate the handling of the folders 20 when withdrawing them from the compartments 26. It will be noted that the cover 23 projects substantially to the front edges 70 of the frames 17 and beyond the bottom 22, thus serving to partially cover the edges of the sheets to protect them from dust and in cooperation with the recesses 29, to provide means for grasping the folder when it is 75 being withdrawn. Conveniently located slidable shelves 32 are also provided to aid in handling the folders. These shelves are provided with pins 33 secured in the edges thereof and which ride in horizontally disposed slots 34 in strips 35 secured to the sides 12 of the cabinet. The slots 34 are closed at the forward end of the strip 35 to limit the movement of the shelves 32. A vertically disposed slot 36 connecting with 90 the horizontal slot 34 provides means for removing the shelves 32 when desired. Apertures 37 are cut in the front edge of the shelves to form hand grips.

When sheets of some flat material, such as inked tracings on cloth used in making blueprints, are to be filed, the most convenient shelf 32 below the compartment 26 in which the tracings are to be filed, is drawn out as far as the slots 34 permit and a folder 100 20 placed flatly thereon. The tracings are then placed in the desired order on the pressboard bottom 22 and covered by the sewed canvas top 23. The folder 20 is longer than the shelf 32 and the shelf may be used as 105 shown in Fig. 1 to aid in filing the folder by tilting the folder on the outer edge of the shelf to insert its sewed edge 24 between the beveled edges 27 of the frames 17 which form the selected compartment 26. The 110

folder is then slid into its filed position in the compartment.

To remove a tracing from the cabinet, the folder in which it is filed is withdrawn a short distance from the compartment, the tracing located and removed, and the folder returned to its filed position.

The beveled edges of the frames 17 serve to remove any creases or wrinkles that might appear in the tracings, and the filled folders 20 lie flat in the compartments 26 under pressure minimizing the probability of the edges of the tracings curling, crumpling, or being torn or damaged in any other way. Also since the folders are pressed tightly between the frames 17 when filed, thus pressing the tracings closely together, air is substantially excluded from between the tracings and their susceptibility to damage by fire is reduced.

What is claimed is:

1. In apparatus for filing sheets of material, an open-front cabinet, a plurality of shelves having beveled front edges mounted horizontally therein and spaced apart to provide a plurality of narrow compartments, and a plurality of containers for sheet material housed within said compartments, each of said containers comprising a rigid

back and flexible cover associated therewith at one edge thereof, the back and the cover of each container engaging the beveled edges of said shelves during the insertion of the containers therebetween to smooth the sheets contained therein and thereafter engaging surfaces of adjacent shelves to maintain said sheets in a smooth condition.

2. In apparatus for filing sheets of material, a cabinet, a plurality of fixed partitions mounted therein and spaced apart to provide a plurality of narrow compartments, and a plurality of containers for sheet material housed within said compartments, each of said containers comprising a rigid back and a flexible cover connected therewith at one end thereof, said partitions having their edges arranged to engage the back and the cover of each container during the insertion thereof to smooth the sheets contained therein, and the upper and lower surfaces of adjacent partitions being engaged by the container for maintaining the sheets therein in a smooth condition.

In witness whereof, I hereunto subscribe my name this 12th day of January, A. D. 1925.

CHARLES JOHN KAY.
